BOTTLE CARRIER

Ralph Cottrel, Dayton, Ohio, assignor of one-third to August L. Pachin and one-third to Franklin R. Pachin, both of Dayton, Ohio

Application May 5, 1948, Serial No. 25,239

4 Claims. (Cl. 224—45)

1

My invention relates to carriers for bottles and other articles of like nature, and particularly for use in carrying bottles containing soft drinks and other beverages, such as beer.

My novel bottle carrier has many advantages, such as being very compact when empty, thus requiring very little storage space since it may be either rolled or folded into a small unit.

Another very important advantage is that, due to my novel neck-forming feature, it securely holds the bottles so that they cannot fall out of the carrier, regardless of the position of the carrier while it is being transported by a person or after it has been laid down or set down.

It is extremely handy for cooling drinks because the carrier with the bottles therein may be placed in a creek or spring water pool when on outings or picnics.

My carrier has excellent wearing qualities because I prefer to make it of a heavy canvas or ducking material.

Therefore, it is an object of my invention to produce a novel bottle carrier, compact when empty and not bulky when filled with bottles.

Another object is to provide a bottle carrier having bottle compartments or pockets formed so as to readily adapt themselves to the contour of the bottles, including the tapered necks of the bottles.

A further object of my invention is to provide a bottle carrier made of two pieces of pliable, limp material sewed together at their ends, and having compartments or pockets formed between the two pieces of material by sewed seams.

A still further object is the provision of a novel bottle carrier of the type just above mentioned wherein the pockets are tapered at one end to make them form fitting for taper-neck bottles to prevent them from slipping out of the carrier, whether the carrier is being carried by either end alone or by both ends together.

Another object of my invention is to provide a novel bottle carrier of the type above mentioned, with carrying handles, one at each end of the carrier, such handles being securely sewed between the two pieces of material.

A further object of my invention is to provide such a type of bottle carrier with pockets or compartments made by sewed seams, and to also provide a blank space between the two center pockets so that when the carrier is picked up by both handles the bottles will be in two groups side by side with the bottles in each group, one above the other in vertical fashion.

With these and other incidental objects in view,

2

my invention includes certain other novel features, as will appear from the drawings and the specification to follow.

Of said drawings:

Fig. 1 is a flat side view of my novel bottle carrier, showing the end seams and how the handles are sewed in between the main pieces of material, and further shows the seams forming the pockets and the neck-forming seams.

Fig. 2 shows an edge view of the carrier, empty and in position to be picked up by both handles.

Fig. 3 shows an edge view of the carrier, partly broken away, with bottles therein, and in position to be picked up by one handle only.

Fig. 4 shows an edge view of the carrier with bottles therein, and in the position it assumes when it is picked up by both of the handles.

Fig. 5 shows a fragmentary section of the bottle carrier and illustrates how the form fitting tapered neck conforms to the contour of the bottle neck.

Fig. 6 is a fragmentary detail, shown in section on line 6—6 of Fig. 1 to show the hemmed edges of the two pieces of material, which hemmed edges are on one side only of the bottle carrier.

Detailed description

As shown in the drawings my bottle carrier comprises two identical sheets 10, made of a pliable limp material, preferably of canvas or heavy ducking material.

Each of the ends of the sheets 10 have turned in hems 11, and the ends of the sheets 10 are sewed together by seams 12. Handles 13 are placed in between the hemmed edges as shown in Figs. 1 and 2, and are stitched securely to the sheets 10.

In my illustrated form I have shown eight 49 seams 14 to form six pockets or compartments 15. As will be noticed from Fig. 1 a blank space 16 is provided between the two center seams 14 to allow enough material for the carrier to assume the shape shown in Fig. 4 when said carrier is full of bottles and is picked up by both of the handles 13.

On one of the long sides of the sheets 10, as shown in Fig. 1 said sheets are provided with turned in hems 17, see also Fig. 6, sewed by seams 18. These hems 17 provide strength for the carrier and prevent stretching of the sheets 10 along this side of the carrier where the bottles are inserted.

Each of the pockets 15 is provided with a neck-forming tapered section by seams 20.

3

These seams 20 begin above the center of the sheets 10 and taper towards one another as said seams approach the outer edges of the sheets 10. It will be noticed that the main or straight seams 14 extend across the entire width of the carrier sheets 10. These seams 14 by extending across the entire width of the bottle carrier prevent that section of the carrier between the smallest ends of the pockets from stretching out of shape and thereby tends to make for better fitting of the neck-forming sections of the pockets 15 around the bottle necks.

In Fig. 1 there are no bottles and therefore, the pockets 15 appear wider because the carrier is here shown flattened out, but in Figs. 3, 4 and 5 the carrier is shown with bottles in the pockets 15. The bottles are designated 22 and when they are put in the carrier they are put in from the side having the seams 17 and pushed into the pockets until the tapered sections formed by the seams 20 conform to the shapes of the bottle necks. Thus the tapered neck-forming sections of the pockets 15 grip the bottles and prevent them from slipping out of the carrier regardless of the position in which the carrier is carried.

When carried by one handle 13 the carrier looks like that shown in Fig. 3. When carried by both of the handles 13 the carrier assumes the form shown in Fig. 4. In this figure can be seen the advantage of the blank section 16, as it permits the bottles to "stack" themselves when the carrier is picked up by both of the handles 13.

From the above description it can be clearly seen that my bottle carrier is not only novel, but that it is a very convenient way to carry several bottles, in a small compact case, and that it has a high utility value.

Furthermore, and as stated at the outset of my specification, in addition to my carrier being compact, and easy to carry when loaded with bottles, due to its construction and the kind of material out of which it is made, it is not necessary to remove the bottles from the carrier when placing the bottles in a creek or a spring water pool to cool the contents of the bottles, since the entire carrier may be deposited with the bottles therein.

As stated before I prefer to make my carrier out of a good grade of canvas or heavy ducking material, to give durability and long wear to the carrier.

However I do not wish to limit my invention to the use of the above stated materials, as other types of materials, so long as they are pliable and limp can be used without departing from the spirit of my invention.

While the form of my invention herein shown and described is admirably adapted to fulfill the objects primarily stated, it is to be understood that I do not wish to limit my invention to the one preferred form which I have illustrated for it is susceptible of other forms, all coming within the scope of the claims which follow.

I claim:

4

1. A bottle carrier comprising a plurality of sheets of pliable material sewed together at their short ends, and having a handle sewed between said ends, and being provided with a plurality of pockets for the reception of bottles, said pockets being formed by seams across the sheets, two of said seams forming a non-pocket area and one side of each of the two center pockets, the pockets on either side of said non-pocket area being adjacent each other, and tapered seams securing the sheets together in said pockets to form sections in the pockets to conform to and grip the tapered necks of the bottles when pushed into said pockets.

2. A bottle carrier comprising a plurality of sheets of flexible, limp material sewed together at their short ends, a handle sewed between the short ends of the material at each end of the carrier, a plurality of groups of pockets formed by seams across said sheets, said groups of pockets being separated by a blank space formed by one seam of each of two of said pockets, and tapered seams securing the sheets together in said pockets at one end thereof to form neck shaped sections in the pockets to conform with the tapered necks of the bottles when said bottles are inserted into the pockets.

3. A bottle carrier comprising two rectangular sheets of flexible material forming the body of the carrier and sewed together at their short ends, and having a handle sewed between said sheets at each of the short ends thereof, a plurality of pockets formed by the sheets by having seams sewed across the sheets, a non-pocket area between the two center pockets, and tapered seams securing said sheets together in said pockets to form neck-forming sections of said pockets to receive and grip the tapered necks of the bottles when said bottles are inserted into said pockets for carrying.

4. A bottle carrier comprising two rectangular sheets of flexible limp material forming the body of the carrier and secured together at their short ends, said sheets being hemmed along the long edges thereof, a plurality of groups of pockets formed by sewing seams across the short widths of said sheets, a tapered section in each pocket formed by sewing the sheets together in said pockets, and a blank space formed by the seam of each of two pockets to form a bottom for the carrier between the groups of pockets when the carrier is picked up by both handles.
